US0D1062691S

(12) **United States Design Patent** (10) Patent No.: **US D1,062,691 S**
 Bian (45) Date of Patent: ** Feb. 18, 2025

(54) **HEADPHONE**

(71) Applicant: **HIFIMAN KUNSHAN TECHNOLOGY GROUP CO., LTD.**,
 Tianjin (CN)

(72) Inventor: **Fang Bian**, Tianjin (CN)

(73) Assignee: **HIFIMAN KUNSHAN TECHNOLOGY GROUP CO., LTD.**,
 Tianjin (CN)

(**) Term: **15 Years**

(21) Appl. No.: **29/885,412**

(22) Filed: **Feb. 23, 2023**

(30) **Foreign Application Priority Data**

Aug. 30, 2022 (CN) 202230569048.X

(51) **LOC (15) Cl.** **14-01**

(52) **U.S. Cl.**

(57) **CLAIM**

The ornamental design for a headphone, as shown and described.

DESCRIPTION

FIG. 1 is a front perspective view of a headphone showing the new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines depict portions of the headphone that form no part of the claimed design.

1 Claim, 5 Drawing Sheets
